DISPLAY CABINET

Charles W. Beck, Toledo, Ohio

Application May 9, 1934, Serial No. 724,782

11 Claims. (Cl. 40—132)

This invention relates to sign cabinets for display purposes on counters and in windows of stores and relates more particularly to the manner of placing the display or advertising matter, which in this invention is on a paper print held between the glass and the frame of the cabinet, and also relates to the manner of supporting and holding the print in the cabinet.

Heretofore advertising matter has been stenciled, painted or otherwise placed on the glass; in consequence, when the glass was broken, the sign was replaced at considerable expense and trouble; further the heat from the illumination cracked the paint and the light faded the colors.

15 In the construction of the cabinet illustrated herein, a photographic print is clamped between the glass and the cabinet front and the marginal edges of the photographic print are held between the outside of the cabinet walls and the frame which telescopes the forward end of the cabinet for the purpose of stretching the print and to 20 keep it smooth.

Further, this invention enables the user to remove the print and replace it with a new and entirely different subject, readily and without trouble.

Fig. 1 is a perspective view of the cabinet illustrating part of a display advertisement thereon.

Fig. 2 is a section of the cabinet on lines A—A 30 of Fig. 1 showing the print, glass and frame in position for assembly.

Fig. 3 is a section of the corner of the cabinet on lines B—B illustrating a cross section of the assembled parts of the cabinet.

35 Fig. 4 is another section of the corner of the cabinet illustrating the frame cut away to show the glass and photographic print with the marginal edges of the photographic print projecting beyond the glass and the ledge on the cabinet for supporting the print, and, also the open corner of the front of the cabinet.

Fig. 5 is a modification of Fig. 4 illustrating the same view with the addition of a second glass under the print as well as over it.

45 Referring to the drawing, 1 represents the rectangular body of the cabinet and which consists of parts 3 which slant towards the back and a straight part 4 over which the frame 5 telescopes. The cabinet is provided with louvres 2 for ventilation and a bracket 15. On the bracket 15 a lamp receptacle 16 is supported which in turn supports a lamp 17. 18 is a source of electric current for the lamp.

The frame 5 is rectangular and as illustrated 55 in Fig. 2 is larger than part 4 of the cabinet, al-

though before assembling the front of the side walls of the cabinet project outwardly and may seem larger than the frame until those walls are forced together and into the frame. The straight parts 8 of the frame are rigid, while the parts 4 of the cabinet are yielding by reason of the open corners 14, Figs. 4 and 5. These open corners of the cabinet permit the sides and ends of the cabinet, parts 4 to be pressed inwardly to force the frame 5 to telescope the front of the 10 cabinet and to exert an outward tension against the marginal edges 11 of the print and hold them in place between the cabinet walls 4 and the inside of walls 8 of frame 5.

As illustrated by the drawing, the frame 5 is 15 made with four vertical walls 8, four horizontal parts 7, four oblique parts 6 and that the parts 6 and 7 of the frame are not joined at any of the four corners 5a. This is done to provide spring tension to part 6 of the frame when forced 20 against the glass 9 and secured in position by screws 19, of which there are two, the opposite not being shown. 9 represents the glass over the print and also the second glass under the print, illustrated in Fig. 5.

25 The body of the cabinet is provided with a back wall and four sides over which the ends are folded as illustrated at 12 and spotwelded at 13. The securing of the ends of the cabinets to the sides by spotwelding is towards the rear, so that 30 the front corners of the cabinet, as illustrated at 14, Fig. 4 and 5, may remain open and be sprung into place under tension when the cabinet, print, glass and frame is assembled.

35 Referring to Figs. 3, 4, and 5 of the drawing, a section of the frame is indicated by numeral 5, the vertical cabinet walls 4 with ledges 20 are shown with glass 9, photographic print 10 with marginal edges 11 and indicator lines 11a of the print in assembled position. For assembly of the 40 print 10 with the cabinet under glass 9, it is folded at right angles along indicator lines 11a and then placed on ledges 20 so that the marginal edges 11 pass outside of the cabinet walls 4; the 45 glass 9 is then placed on the print with the outside edges of the glass in register and paralleling lines 11a of the print. It will be noted that the corners of the print have been cut away to permit the marginal edges 11 to fold at right angles so that when the frame is placed over the 50 cabinet, the telescoping parts of the frame 5 will hold the marginal edges 11 of the print clamped between the inside walls of the frame and the outside of the side walls 4 of the cabinet, as illustrated in Fig. 3. The frame 5 is secured to the 55

cabinet by screws 19 with parts 6 of the frame under tension and against the upper side of glass 9. This tension of the frame against the glass is brought about by reason of corners 5^a being 5 separated so that each side of the frame, part 6, exerts a pressure on the glass when secured into position on the cabinet, the separation shown at 5^a rendering the part 6 of the frame springy. The side walls 4 of the cabinet are resilient by 10 reason of the separation at the corners as indicated at 14, so that when the frame is placed over the cabinet walls with the print and glass in position, the marginal edges 11 of the print are firmly held between the side walls 4 of the cabinet 15 and the vertical walls 8 of the frame and the frame and cabinet are secured in that position by screws 19.

For assembling, the cabinet is placed on its back, the photographic print is next placed on ledge 20 with the glass 9 over it substantially flush with part 4 and lines 11a on the print; a cloth is then used to rub along the edges of the glass and print to fold the marginal edges 11 of the print downward along lines 11a; the frame is then 25 telescoped over one corner of the glass, print and part 4 of the cabinet and the other corners in turn pressed in and the frame telescoped over the cabinet all around; this closes slots 14 and leaves the print stretched and smooth, after which the 30 two screws at opposite ends are inserted through holes in the frame which register with holes in part 4 of the cabinet.

The process of making the photographic print and the coloring of it, is a distinct and separate 35 invention and will be claimed by applicant in another application.

What I claim herein, is:

1. A display cabinet having resilient side walls separated from each other at the front thereof, 40 means on said side walls for supporting display material, a print and a glass over said print supported by said means and a frame for telescoping the side walls to hold the side walls together and to hold the display material in position.

45 2. A display cabinet having side walls separated at the front thereof by slits, said side walls being provided with ledges, a frame for holding the side walls together to close the slits, display material supported between the ledges of the side walls and the frame and members on said frame for resiliently clamping the display material.

50 3. A display cabinet having free and resilient side walls with a part for supporting display material, a print and a glass on said print, a frame for telescoping the side walls of said cabinet and clamping the print between the side walls of the cabinet and the frame and means for holding the frame in position.

55 4. A display cabinet having a body member 60 with a rigid back and resilient side walls, the side walls being separated from each other at the front of the cabinet and being formed with a ledge, for the support of display material, a frame to telescope and close the resilient side walls and to 65 hold the display material in position and means for securing the frame in closed position.

5. A display cabinet body with a rigid back and 70 resilient side walls, said side walls forming when closed a continuous ledge for the support of display material and being separated near said ledge,

a print, glass on both sides of said print supported on said ledge, a frame telescoping the resilient side walls of the cabinet body to hold the display material in position and means for fastening the frame on the cabinet body. 5

6. In a display cabinet having the rear part of the walls and part of the side walls of the body member rigid and the front part of the side walls resilient and with slits between them and formed to support display material, a print, a frame, and 10 a glass in said frame, said frame having fixed members to telescope the resilient side walls of the front part of the body of the cabinet, and horizontal members on said frame for holding the glass and print between the frame and the body 15 of the cabinet and means for securing the frame in fixed relation on the body of the cabinet.

7. A frame for closing an illuminated body member, a glass supported between the frame and the body member, said frame comprising a telescoping member to embrace said body member and members at right angles and integral with the telescoping member on said frame to hold the glass under tension, the latter mentioned members of said frame being slotted at fixed intervals 20 to permit said members to exert spring tension on said glass, and means for securing the frame to the body member. 25

8. A display cabinet with separated side walls for the support of display material thereon, a 30 frame for telescoping the side walls and forcing them into contact with each other at the point of separation, a print provided with marginal edges with the marginal edges arranged at right angles to the face of the cabinet and clamped 35 between the side walls of the cabinet and the telescoping members of the frame and means for securing the frame in assembled position.

9. A display cabinet comprising a body member with side walls separated from each other at the 40 corners and a frame adapted to telescope the side walls of the body member and bring them together under tension to clamp display material between the outside of the side walls of the body member and the telescoping members of the frame. 45

10. A display cabinet comprising a body member and a frame, said body member having side walls separated from each other by slits, the frame being provided with members for telescoping the side walls of the body member and bringing them together under tension, and a print for display provided with overlapping ends in engagement with the outside of the sidewalls of the body member and the telescoping members of the frame to secure it in position. 55

11. An illuminated shell having walls of opaque material closed in every direction except for ventilation and having an open front, a glass for closing the front of said shell, a frame for holding the glass in position on said shell, said frame comprising a telescoping part to embrace said shell and members at right angles and integral with the telescoping part on said frame to hold the glass under tension against said shell, the latter mentioned members on said frame being slotted at 60 intervals to permit said members to exert spring tension on said glass and means for securing the frame to the shell to hold the glass in position. 65
